Primary Examiner — John Windmuller*Assistant Examiner* — John R Yeh(74) *Attorney, Agent, or Firm* — Shun Yao; Park, Vaughan, Fleming & Dowler LLP(57) **CLAIM**

The ornamental design for a radio system, as shown and described.

DESCRIPTION

FIG. 1 presents a frontal perspective view of the radio system. FIG. 2 presents a back perspective view of the radio system. FIG. 3 presents a front view of the radio system; and, FIG. 4 presents a back view of the radio system. The broken lines in the figures represent features of the radio system that form no part of the claimed design. The company logo in FIG. 4 forming part of the claimed design is a registered trademark of Ubiquiti Networks, Inc.
